T. F. MANNS

SPECIFIC GRAVITY BALANCE

Filed Oct. 2, 1925

INVENTOR:

Thomas Franklin Manns

UNITED STATES PATENT OFFICE.

THOMAS FRANKLIN MANNS, OF NEWARK, DELAWARE.

SPECIFIC-GRAVITY BALANCE.

Application filed October 2, 1925. Serial No. 60,110.

This invention is a new and improved specific gravity balance for obtaining accurate and dependable readings of specific gravities of boiling and cold solutions, both 5 heavier and lighter than water, being particularly adapted for quick readings of specific gravities of rapidly boiling tomato pulp, while being reduced to tomato purée by copper coils containing 50 to 125 lbs. 10 of steam pressure, a particularly difficult task because of the turbulent boiling and the rapid change or reduction in temperature during sampling. The following is a full, clear, and exact description.

15 This invention relates to an improved balance for reading directly the specific gravities of boiling and cold (at 20° C.) tomato pulp, catsup, tomato paste or other boiling or cold solutions. The invention 20 which is new is a beam (see Fig. 1) so graduated and standardized on the lower part to read the specific gravities of both boiling and cold (at 20° C.) solutions, when same is properly sampled in a 500 ml. volumetric 25 flask and counterbalanced by proper weights; the upper part of the beam is graduated and standardized to read grams, thus aiding the manufacturer to more quick-

ly standardize the balance. The balance which is furnished with a compensating 30 weight to counterbalance the special 500 ml. volumetric flask, is so standardized and graduated on this improved beam, as to require, for specific gravities of boiling pulp from 1.025 to 1.045, an initial weight of 35 492.5 grams, and for cold pulp at 20° C. for the same range of specific gravities the 492.5 gram weight and a 19.5 gram weight. Other specific gravities of boiling or cold solutions may be graduated on a similar improved beam and balance, by adding or deducting to the weights to offset such specific 40 gravities.

Having fully described my invention 45 what I claim as new is:

A beam, for reading the specific gravities of boiling or cold solutions, having graduations on its upper side representing grams and graduations on its lower side representing specific gravity, adapted for reading 50 tomato pulp, catsup or any solution sampled while boiling or cold in a suitable flask (a 500 ml.) and counterbalanced by proper weights.

In testimony whereof I affix my signature.

THOMAS FRANKLIN MANNS.
